UNITED STATES PATENT OFFICE

GEORGE H. ROUNDS, OF NAPLES, MAINE

DESIGN FOR A CABINET FOR RADIORECEIVING APPARATUS

Application filed April 4, 1932. Serial No. 43,389. Term of patent 14 years.

To all whom it may concern:

Be it known that I, GEORGE H. ROUNDS, a citizen of the United States, residing at Naples, in the county of Cumberland and State of Maine, have invented a new, original, and ornamental Design for a Cabinet for Radio Receiving Apparatus, of which the following is a specification, reference being had to the accompanying drawing, forming a part hereof.

Figure 1 is a perspective view of a cabinet for radio receiving apparatus in accordance

with this invention in open position, showing my new design.

Figure 2 is a similar view of a cabinet for radio receiving apparatus in closed position, showing my new design.

Figure 3 is a perspective view looking towards the rear of the cabinet.

I claim:

The ornamental design for a cabinet for radio receiving apparatus, as shown and described.

GEORGE H. ROUNDS.
